UNITED STATES PATENT OFFICE.

HUBERT SPENCE THOMAS, OF LLANDAFF, AND WILLIAM ROBERT DAVIES, OF WHIT-
CHURCH, WALES.

MACHINE FOR DOUBLING TIN PLATES.

Application filed January 26, 1925, Serial No. 4,953, and in Great Britain February 2, 1924.

Our invention relates to machinery employed in the manufacture of tin-plates, sheets or the like and more particularly to the machinery whereby the preliminary 5 doubling or folding operations are performed for obtaining from the pieces or bars of steel what are technically known as "black plates" or "sheets."

In the specification of Letters Patent No. 10 1,535,876, granted to us and issued the 28th day of April 1925, we have described and claimed a process of effecting the said doubling or folding operations by submitting the plates or sheets to endwise pressure, the said 15 specification describing and illustrating a machine for carrying the invention into effect.

The present invention consists of the hereinafter described improvements in or modifications of certain parts of the said machine, the said improvements or modifications having for their principal objects to reduce to a minimum the amount of scrap metal produced when the doubled or folded 25 plates or sheets are submitted to the shearing operations which intervene between each successive doubling or folding operation, to effect the more complete compressing together of the folded plates or sheets especially along the folded edge thereof, and 30 generally to increase the efficiency of the machine.

The improvements constituting the present invention will be further described with 35 reference to the accompanying drawings which illustrate somewhat diagrammatically convenient means or mechanism for carrying the invention into effect.

Figure 1 represents in side elevation a 40 plate or sheet doubling or folding machine embodying the improvements constituting the invention, the traveling pressure member of the machine being indicated in dotted lines only and a partially folded plate being 45 also shown in dotted lines.

Figure 2 is a plan of the machine, certain parts hereinafter referred to being omitted or broken away. The travelling pressure member is shown in full lines in 50 this figure.

Figure 3 is a cross section on the line 3-3, Figure 1, and looking in the direction of the arrow A in the said figure.

Figure 4 is a sectional side elevation of 55 the rolls and parts co-operating therewith

to improve or complete the fold of the plates or sheets and deliver them from the machine, a folded plate or sheet being shown in full lines and indicated in dotted lines in positions which it assumes during delivery from 60 the machine.

Figures 5 and 6 are sectional side elevations of a portion of the left hand end of Figure 1, drawn to an enlarged scale, and disclosing parts of the mechanism herein-after more particularly referred to, the several parts of the said mechanism being shown in the said figures in the extremes of positions which they assume during the operation of the machine. 70

The same numerals of reference indicate the same parts in the several figures of the drawings.

Before referring to those parts of the machine or mechanism wherein the improvements or modifications which constitute the present invention more particularly reside we remark that the reference 7 and 8 denote the end standards of the machine and 9 the pressure exerting member which is adapted to be traversed on tracks provided by the upper and lower pairs of longitudinal bars 10 and 10^a respectively which connect the said end standards, the pressure exerting member 9 being provided with anti-friction devices or rollers 9^a for travelling on the tracks. 75 80 85

As in the prior Patent No. 1,535,876 filed March 23rd, 1922, and issued April 28th, 1925, the pressure exerting member 9, when 90 travelling in the direction of the arrow A in Figure 1 co-operates with the end standard 8 or parts carried thereby to put the requisite pressure on the plate or sheet for effecting the doubling or folding thereof, a partially doubled plate, marked X, being shown in Figure 1 and indicated in dotted lines in Figure 2. 95

The traversing or reciprocatory motion of the member 9 can be effected by a hydraulic ram or other convenient means as for example by the mechanism illustrated which comprises the pair of parallel endless chains 11 supported by and travelling over the sprocket wheels 12, 12^a, 12^b and 12^c, the spindles of which are conveniently supported in bearings provided in the longitudinal side bars 10 and brackets 13 provided thereon, the spindles of the sprocket wheels 12 and 12^a also having thereon sprocket wheels 100 105 110

14 geared to the sprocket wheels 15 on the shaft 16 which is geared to and driven from the armature shaft of the electromotor 17.

We will now refer to the improvements in or modifications of the machine or mechanism constituting the present invention, and in order that the manner in which we effect a reduction in the amount of scrap metal produced in the shearing operations which 10 intervene between successive doubling or folding processes may be the better appreciated, we remark that one end or edge of the plate or sheet, or multiple ply of plates or sheets to be folded, ordinarily has 15 a more or less irregular concave formation, projecting parts or ear pieces being produced thereon by the rolling operation which precedes the folding process, and when the said folding process has been performed and 20 the straight edge of the sheet has been brought thereby into juxtaposition with the irregular edge, the amount of the straight edge which will be cut away in the succeeding shearing operation for trimming the 25 irregular edge will depend on the relative position or overlap of the said edges after the doubling process.

In operating with the doubling machine of the prior patent hereinbefore referred 30 to, it has been customary to arrange the projecting hooks or arms which are provided for lifting the doubled plates or sheets into the rolls which complete the doubling operation and transfer the folded 35 plate or sheet from the machine somewhat below the level of the platform or bed on which the plates or sheets rest when delivered to the machine and on and along which the straight edge bears and travels 40 during the folding process. By such arrangement the irregular or concave edge of the sheets, which edge is presented to and adjacent the hooks or arms and as the folding proceeds is brought to rest and bears 45 thereon, is, on the completion of the fold, at a correspondingly lower level than the straight edge of the sheet, overlapping the same to the extent or approximately to the extent of the irregular portion and thus reducing the amount of the straight edge cut 50 away in the trimming operation.

It is however found in practice that the extent of the irregularity produced at one 55 end of the sheets by the rolling operations varies considerably after each successive fold and consequently a definite or fixed setting of the hooks or arms referred to does not therefore operate to reduce waste to the maximum extent possible in the shearing operation following each successive folding 60 process.

According to the present invention for the purpose of rendering necessary only a minimum cutting away of the straight edge of 65 the folded sheet in the shearing operation

following each successive folding process the hooks or arms referred to, or preferably a single hook or arm replacing the same and arranged on the center line of the machine, which hook is hereinafter referred to as the 70 gauge hook, is so mounted on the machine as to be capable of being set to predetermined positions according to the extent of the irregularity which will be required to be removed on the following shearing operation. 75

A convenient construction and arrangement of the said gauge hook and its adjusting mechanism is illustrated in the drawings and best seen in Figures 5 and 6, from an examination of which it will be seen that the 80 gauge hook marked 18 is mounted on or formed integral with a rod 18^a arranged to slide in a guide 19, or guides, provided on the framing or end standard 8 of the machine. The said rod extends upwardly and 85 passes through a slot 8^a in the standard 8, its upper end, being pivotally connected with the lever or crank arm 20 on the shaft or spindle 21 supported in bearings in the opposite sides of the standard, one or both ends 90 of the said shafts projecting beyond the standard and being provided with a lever 22 in convenient position for manipulation by the attendant, the said lever, which is seen only in dotted lines in Figures 5 and 6, having means combined therewith for engaging 95 with one or other of a series of notches in a rack 23 for retaining it in the position to which it may be adjusted after the manner of a change gear or similar lever mechanism. 100

In order to ensure that the irregular forward edge of the plate or sheet X shall be caused to take its bearing on the gauge hook 18 instead of rising up when the end pressure is brought to bear on the plate or sheet, we provide preferably a pair of pivoted plates or flaps 24 adapted in the working of the machine to be automatically turned down on to the said front edge when the plate or sheet to be folded is in position on the platform or bed 25, the said retaining flaps 24 being automatically returned to their out of action position as the folding operation proceeds. 105

Each pivoted flap or plate 24 is conveniently mounted on a pivot 26, or a continuous shaft supported on the end standard or frame 8, and is operated through the medium of a link 27 attached to an arm or bracket 24^a thereon, the requisite motion of which is effected by a bell crank lever 28 provided with a counterbalance weight 28^a, the said lever being fulcrumed on the shaft 29 journalled in brackets on the standard 8, the operation of the said levers synchronously with the other motions of the mechanism being effected by tappet rod mechanism actuated by or through the movable pressure exerting column 9 of the machine. 115

The said tappet rod mechanism conven- 120

iently comprises a rod 30 adapted to slide in guides 30^a on the underside of the platform 25, and the said rod may operate one of the levers 28 by bearing directly on but without positive connection or attachment to the depending extension 28^b of the said lever; but preferably the said extension 28^b and tappet rod 30 are coupled by a link 31 as shown in the drawings. The operation of the one bell 5 crank lever effects the simultaneous motion of the other bell crank lever, the said levers in addition to being fixed on the same shaft 29 being preferably joined at their lower ends by a spindle 29^a.

Convenient means for effecting the reciprocatory motions of the tappet rod 30 for lowering and raising the pivoted flaps or plates 24 at the requisite times during the travel of the member 9 comprises the provision on the said member 9 of arms or levers 32 and 33 (see Figure 1) depending from the horizontal rod or bar 34. The lever 32 is preferably adjustably mounted on the bar 34 and the lever 33 is pivoted at its upper end to the said bar and is also pivoted at the point 33^a intermediate its ends to a plate or bracket 10^b on the frame bar 10^a, the said bracket preferably providing for an adjustable positioning of the fulcrum or pivot 33^a. The lower ends of the levers 32 and 33 are furnished with pivoted sections 32^a and 33^b respectively, which sections conveniently comprise pairs of parallel and connected bars disposed one on each side of the upper sections of the levers. The said pivoted sections by the action of the respective cross pins 32^b and 33^c remain rigid with their upper sections when the arm 9^a of the pressure member acts thereon in its forward motion, but turn relatively to their upper sections when the said arm is travelling in the opposite direction.

The bar 34 is pivoted at one end to the lever 35 fulcrumed at 36 to the standard 7, the short arm of the said lever being provided with a pin or stud adapted to work in a slot in the arm or crank 37 on the shaft 38 which crosses the end standard 7 transversely and has mounted thereon the lever arm 39 the free end of which engages in a slot 80^b in the tappet rod 30. The shaft 38, crank 37 and lever arm 39 thereon which are indicated in dotted lines in Figure 3 are not properly seen in the said figure having been cut away by the taking of the section on the line 3—3, Figure 1.

From the above description of the tappet mechanism it will be understood that as the pressure exerting member 9 travels in a forward direction, that is, in the direction of the arrow A, after a plate to be doubled has been delivered on to the platform 25, the cranked bar 9^b carried by the said member first contacts with the part 32^a of the depending two part lever 32, 32^a which travels forward, the bar 34 receiving motion in the same direction, thus turning the levers 33 and 35 on their fulcrums 33^a and 36 into the oppositely inclined positions to that in which they are shown in Figure 1 of the drawing. The motion of the lever 35 is transmitted through the crank 37 to the shaft 38, the lever arm 39 thereon thus receiving motion in a direction proper to draw the tappet rod 30 rearwardly and effect through the bell 75 crank levers 28 and parts already described in connection therewith the turning of the retaining flaps 24 from the turned up position illustrated in Figure 6 into the turned down or retaining position seen in Figure 5 in which position the flaps are brought to bear on the plate X.

While the bar 34 is moving longitudinally it is also partaking of a rising motion due to its lever connection with the pivots 33^a and 36, and thus the depending member 32, 32^a is raised and permits the cranked arm 9^b to pass. The continuing motion of the pressure member 9 brings the said arm 9^b into contact with the compound lever member 33, 33^b, which member is now inclined in the opposite direction to that seen in Figure 1, and the reversal of motion of the tappet rod operating parts is effected, the tappet rod being caused to move in the opposite direction and through its action on the bell crank levers and connected parts to raise the flaps out of the path of the forwardly travelling pressure member 9.

The cranked arm 9^b has now passed the depending part 33^b and the pressure member completes its forward stroke. On the back stroke of the said pressure member the pivoted parts 33^b and 32^a yield and ride over the cranked arm 9^b.

The end of the plate X in contact with the pressure member is preferably restrained from rising off the platform by the overhanging end of a plate or shoe 40 suitably mounted on the pressure bar.

Instead of utilizing the hook 18 to raise the folded sheet into the nip of the rolls 41, 42 or transferring mechanism, in addition to forming the stop for the irregular edge of the plate, which dual function was 115 performed by the corresponding part in our prior patent referred to, we prefer to employ independent means for effecting the lifting operation. Convenient mechanism for the said purpose may comprise an endless chain, or preferably as shown in the drawing, see the plan Figure 2, a pair of parallel endless chains 43 travelling over sprocket wheels 44, the said chains being provided with a projecting pivoted arm or finger 45 adapted to be brought by the motion of the chains, which is synchronized with the other motions of the machine, into position below the lower edge of the folded plate or sheet, as seen in Figure 6, the plate 125 130

or sheet being thereby lifted into the rolls or transferring mechanism.

The synchronous motion of the chains 43 may be effected through the sprocket wheel 5 44^a on the spindle of the sprocket wheel 44, said wheel 44^a being geared by the chain 44^b to the sprocket 44^c on the spindle of the roller 42, the said spindle being geared by a spur wheel 42^b with a spur wheel 42^c on 10 the spindle of the roller 42^a, which roller is hereinafter more particularly referred to, the spindle of the roller 42^a being provided with a sprocket wheel 42^d driven by the chain 12^e from the sprocket wheel 12^d on 15 the same spindle as the sprocket wheel 12^c of the gearing which effects the traverse of the pressure member 9.

To avoid undue friction between the longitudinal edges of the plates or sheets being 20 folded and the longitudinal guide bars or webs 46 and 47 between which they are positioned on the platform 25, which friction is liable to occur as the sheet takes the arched formation during the folding operation, we 25 space the said guide bars or webs at a distance apart somewhat greater than the width of the sheets, and in order to effect the gripping of the lower ends of the folded sheets between the said guides at or near the completion of the folding operation one of 30 the said webs or guides, namely 47, or a portion thereof is so pivoted at 48 that it can be turned inwardly and made to bear with the requisite pressure against the lower 35 ends of the folded sheet which are thus gripped between the fixed and movable guide bars or webs. The inward turning of the said web or bar 47 or part thereof can be conveniently effected by providing on its 40 outer face an inclined portion on which the movable pressure exerting member 9 or a laterally projecting arm 9^c thereon is adapted to act in its forward motion.

Or instead of providing an inclined part 45 directly in the guide bar or web 47 for the arm 9^c to act against we prefer to provide the inclined slotted bar 49 pivoted at one end to a bracket 50 on the longitudinal frame bar 10^a, the slot 49^a of the said bar accommodating a pin 51 the position of which is 50 adjustable in the slot 49^a, the said pin being connected by links 51^a to a pivot 52 carried by a bracket on the guide bar or web 47.

Pressure of the arm 9^c of the travelling member 9, when the same is nearing the end 55 of its forward motion, on the slotted bar 49 acts through the links 51^a to move the web 47 into contact with the lower side edges of the arched plate during the latter part 60 of the folding operation and ensures the even folding of the plate, the said lower parts of the plate being correctly positioned between the opposite side webs 46 and 47. The web 46 is omitted from the plan Figure 65 2 but is seen in section in Figure 3, and in

order the better to disclose the slotted bar 49 and parts connected therewith and also the arm 9^c on the member 9, the upper longitudinal frame member 10 on the side at which the said parts are arranged is shown 70 in Figure 2 partly broken away.

Preferably the face of the end standard 8 against which the folded sheet is compressed by the pressure exerting member 9 is slightly inclined outwardly, the acting 75 face of the movable pressure exerting member having a corresponding inclination so that when the pressure exerting member recedes there is no tendency for the folded sheet to fall backwards.

Or we may interpose between the said presented faces a pair of guide plates 53, 54 between which the doubled sheet passes as it is lifted to the rolls or transmission mechanism, the plate 54 being hinged as 85 at 54^a to a bracket on the frame bar 10, see Figure 6, and retaining the doubled sheet in position when the pressure member 9 recedes.

In the patented machine hereinbefore referred to the means for facilitating the transfer of the folded plate or sheet from the machine comprised a pair of rolls arranged side by side and transversely across the machine after the manner of the rolls 90 41 and 42 into the nip of which rolls the folded plate or sheet is raised, the said rolls serving by their pressure to improve the fold of the plate or sheet.

According to the present invention we 100 modify the said transfer means by combining therewith an additional transverse pressure roll 42^a arranged above the outer roll 42 of the side by side pair. The side by side rolls 41 and 42 are adapted to constitute conveyer rather than nipping or pressure rolls and serve to transfer the sheet to an inclined guideway or platform 56 (not shown in Figures 2 and 3) arranged adjacent the rolls. The sheet X is delivered on to the guideway or platform with its 105 folded edge remote from the pair of rolls 42 and 42^a, and thus in sliding down the guideway the unfolded edges of the sheet first 110 pass into the nip of the said rolls, as will be best understood by an examination of Figure 4, which shows the folded sheet X is full lines rising from between the rolls 41 and 42 and being deflected by the deflector plate 57 on to the inclined guideway 56 whereon it is indicated in dotted lines, the sheet being also indicated in dotted lines in the said figure after sliding from the 115 guideway and passing between the pressure rolls. By the arrangement described the conveyance of the folded sheet from the machine is facilitated and the completion of the fold by the vertically acting pressure rolls is improved.

If desired the inner roll 41 of the side by 120

side pair may be replaced by a series of roller disks or wheels.

By the above described improvements in or additions to the machine of the prior patent hereinbefore referred to the doubling or folding operations on the plates or sheets are facilitated and rendered more efficient, greater accuracy in the folding and less waste in the intervening and final shearing operations on the folded plates or sheets or multiply of plates or sheets resulting.

Claims:—

1. A machine for doubling tin plates comprising means for applying end pressure to the plate to effect an initial doubling thereof, a bed for preserving the position of the ends of the plate during the initial doubling operation, a gauge hook slidably mounted relative to said bed and capable of adjustment relative thereto, means for completing the doubling of the plate and means for effecting the delivery from the machine of the doubled plate.

2. A machine for doubling tin plates comprising means for applying end pressure to the plate to effect an initial doubling thereof, a bed for preserving the position of the ends of the plate during the initial doubling operation, a gauge hook slidably mounted relative to said bed and capable of adjustment relative thereto, automatically operable retaining means for causing the plate to take the proper bearing on the gauge hook on the application of endwise pressure to the plate, means for completing the doubling of the plate and means for effecting the delivery from the machine of the doubled plate.

3. A machine for doubling tin plates comprising a traversable member adapted to apply endwise pressure to the plate to effect an initial doubling thereof, a bed for preserving the position of the ends of the plate during the initial doubling operation, a gauge hook slidably mounted relative to said bed and capable of adjustment relative thereto, automatically operable retaining means for causing the plate to take a proper bearing on the gauge hook on the application of endwise pressure to the plate, means operated by the aforesaid traversable member for effecting the actuation of said retaining means, means for completing the doubling of the plate and means for effecting the delivery from the machine of the doubled plate.

4. A machine for doubling tin plates comprising a traversable member adapted to apply endwise pressure to the plate to effect an initial doubling thereof, a bed for preserving the position of the ends of the plate during the initial doubling operation, a gauge hook slidably mounted relative to said

bed and capable of adjustment relative thereto, automatically operable retaining means for causing the plate to take a proper bearing on the gauge hook on the application of endwise pressure to the plate, means operated by the aforesaid traversable member for effecting the actuation of said retaining means, a pair of rolls for completing the doubling of the plate, means for transferring the partially doubled plate to the said rolls and means for effecting the delivery from the said rolls of the doubled plate.

5. A machine for doubling tin plates comprising a traversable member adapted to apply endwise pressure to the plate to effect an initial doubling thereof, a bed for preserving the position of the ends of the plate during the initial doubling operation, a longitudinally extending member adjacent said bed adapted to be moved inwardly by the traversable member, a gauge hook slidably mounted relative to said bed and capable of adjustment relative thereto, automatically operable retaining means for causing the plate to take a proper bearing on the gauge hook on the application of endwise pressure to the plate, means operated by the traversable member for effecting the actuation of said retaining means, a pair of rolls for completing the doubling of the plate, means for transferring a partially doubled plate to said rolls and means for effecting the delivery from the said rolls of the doubled plate.

6. A machine for doubling tin plates comprising a traversable member adapted to apply endwise pressure to the plate to effect an initial doubling thereof, a bed for preserving the position of the ends of the plate during the initial doubling operation, a longitudinally extending member adjacent said bed, means on the member for effecting the inward motion of the said longitudinally extending member, a gauge hook slidably mounted relative to said bed and capable of adjustment relative thereto, automatically operable retaining means for causing the plate to take a proper bearing on the gauge hook on the application of endwise pressure to the plate, means operated by the traversable member for effecting the actuation of said retaining means, a pair of rolls for completing the doubling of the plate, means for transferring a partially doubled plate to said rolls, means for effecting the delivery from the said rolls of the doubled plate and means for effecting the motion of the traversable member and of the rolls.

In testimony whereof, we have signed our names to this specification.

HUBERT SPENCE THOMAS.
WILLIAM ROBERT DAVIES.
